RAZOR BLADE BOX

Edwin A. Locke, Jr., Quincy, Mass., assignor to
The Nevins-Church Press, New York, N. Y.

Application February 21, 1946, Serial No. 649,153

6 Claims. (Cl. 229—27)

1

This invention relates to new and useful improvements in boxes for razor blades and has especial reference to one in which new as well as used blades may be therein disposed.

As is well known, used razor blades constitute quite a disposal problem, and it is the main object of this invention to provide a device in which this problem is solved in the simplest and most logical and efficient manner.

A further object is to provide a box or carton in which the new and used blades can be kept together but in separate compartments, in other words when you buy the new blades you are provided with means for storing or disposing of the used blades at the same time.

Still another object is to provide a box which preferably is formed into one or more modifications of box from a single-piece blank which can be folded either by hand or machinery and then assembled either by machinery or by hand to form the box.

Further and more specific objects, features, and advantages will more clearly appear from the specification hereinafter set forth especially when taken in connection with the accompanying drawings which illustrate present preferred forms which the invention may assume and which form part of the specification.

In the briefest and most general terms the invention includes a box blank with foldable sections forming end and side walls and an intermediate partition to form separate, spaced, preferably vertical chambers, one for the new blades and one for the used blades. The partition wall is provided with a slot near its top into which the used blades can be inserted for disposal into one of the chambers. The box is provided along the top of one end wall with a separable portion connected to the top of the box so that when the separation takes place the top and upper side of the chamber containing the new blades are exposed as well as the slot in the partition wall. In this manner, therefore, the new blades are readily accessible and the slot is available for the disposal of the used blades. The only other difference in the two forms shown is, that in one form the flaps and connecting means are adapted to be assembled and related by machinery and glued together, whereas in the other form the flaps are provided with locking tabs whereby the flaps and sections may be held in relative position without gluing and may be assembled by hand.

The present preferred forms which the invention may assume is illustrated in the drawings of which,

2

Fig. 1 is a perspective view of one form of the box;

Fig. 2 is a vertical cross section taken on the line 2—2 of Fig. 1;

Fig. 3 is a horizontal cross section taken on the line 3—3 of Fig. 2;

Fig. 4 is a perspective view of the box showing the top pulled up exposing the new-blade chamber;

Fig. 5 is a plan of the entire box blank for the form of box;

Fig. 6 is a perspective view of another form of box;

Fig. 7 is a vertical section taken on the line 7—7 of Fig. 6;

Fig. 8 is a horizontal cross section taken on the line 8—8 of Fig. 7;

Fig. 9 is a perspective view of this form of box showing the cover lifted by breaking it along the 20 serrated line; and,

Fig. 10 is a plan view of the blank for this form of box.

In the first form of box shown in Figs. 1 to 5 inclusive, the blank is provided with a plurality of fold lines A, dividing it into the following sections, namely, a connecting section 10, an intermediate partition wall section 11, another connecting section 12, the rear end wall section 13, a side wall section 14, the front end wall section 15, and another side wall section 16, two bottom flaps 17 and 18 connected respectively to the rear end and front end wall sections 13 and 15. Flaps 19 and 20 are connected respectively to the top of the front end and rear end wall sections 15 and 13. A flap 21 is connected to the top of the intermediate partition wall section 11 and has a horizontal creased line 25 running medially thereof. The front end wall section is provided with a horizontal slit 24 near its top edge and with vertical weakened lines 23 running up from the ends of the slit 24 to the top of the wall along the lines of fold. The intermediate partition wall section is also provided with a slot 26 near its top.

In assembling the blank its two outer ends are drawn toward the observer. Then referring to Figs. 2 and 3 it will be seen that the connecting section 10 is disposed against the left portion of side wall 14 with the partition wall section 11 disposed between the front end and rear end wall section 15 and 13 thus dividing the box into two chambers the one on the left for used razor blades and the one on the right for new blades.

The connecting section 12 lies against the left portion of the other side wall section 16 which has been bent around from the front end wall section

16. The bottom flaps 17 and 18 are folded up and glued together. The connecting sections 10 and 12 are glued to their respective side wall sections. As seen in Fig. 2 the lower half of the flap 21 is bent over the top of the left hand chamber and the upper half of flap 21 is bent back against the lower half and receives the end of the flap 19 connected to the front end wall section 15. These flap portions are glued together. Then the flap 20 is bent down over them and glued in place.

It will then be observed that assuming the right chamber to be filled with new blades, that when one wishes to get a new blade he breaks the upper portion of the front end wall section 15 above the slit 24 and this will permit it and the top wall to be raised as shown in Fig. 4 whereupon the upper end of the chamber for new blades is exposed so that the new blades can be readily reached and at the same time the slot 26 in the partition wall 11 is also exposed and available so that used blades may readily be slipped there through.

This particular form of blank is particularly adapted for machine assembly and filling.

In the form shown in Figs. 6 to 10 inclusive, the blank is shown in Fig. 10 and has lines of fold A shown in dot and dash lines.

This modified form of box blank is also provided with the same sections 10 to 16 inclusive, and 21, but in other respects has been changed to make this form one which is especially adaptable for hand assembly and filling. The partition wall section 11 is still provided with the slot 26 near its top through which the used blades are inserted into the left hand chamber, and the front end wall section 15 is provided as before with the slit 24 and the weakened lines 23.

The changes in this form of box blank over the previous one are that the flap 21 in its upper part is now employed as a lock tab 21', the flap 19 now has an upper attached lock tab 19', there are small flaps 14' and 16' at the bottom of the sections 14 and 16 respectively and the flap 17 has a lock tab 17' attached to its lower edge.

Since this form of box blank is adapted to be assembled by hand and without any glue the procedure is as follows:

Assume, as before that the ends of the blank are drawn toward the observer, and referring to Figs. 7 and 8 it will be seen that, as before the connecting section 10 lies against the left portion of the side wall section 14 with the partition wall section 11 between the end wall sections 13 and 15, the connecting section 12 will lie against the left portion of the side wall section 16. However, in this form the flap 21 lies over the left chamber formed by end wall section 13 and partition wall section 11 and its lock tab is tucked down inside the top of the end wall section 13 (Fig. 7). The small flaps 14' and 16' are bent up to lie flat towards each other and the flap 17 lies beneath them with its lock tab 17' tucked up inside the lower portion of end wall section 15. The flap 19 lies over the top of the box and its lock tab 19' is tucked down inside the top of end wall section 13 and between it and the lock tab 21' as shown.

With the right chamber filled with new blades and the parts assembled as described, to open the box it is merely necessary, as before, to pull up on the upper portion of end wall 15 at the slit 24 and break this portion away to lift the top and expose the chamber with the new blades therein and also to expose the slot 26 for the

reception of the used blades when desired. Of course it is possible in this form to lift the top flap 19 as shown in Fig. 9 entirely off the box in which case the chamber for the used blade is still covered.

It will therefore be seen that in these forms there is provided a box made from an integral one-piece blank which when assembled provides two chambers with an intervening partition wall, one chamber intended for new blades and the other for used blades, the partition wall having a slot near its top to pass used blades into the chamber for used blades. Preferably the right hand chamber which is exposed when the cover is torn open is the one for the new blades and the left hand chamber which is always covered is the one for the used blades. In each case the box has a top cover flap which is pivoted to lift up and connected to the upper portion of the front end wall which is separable by reason of the weakened creased lines to lift it and the cover to expose the top of the one chamber and expose the partition with the slot therein.

While the invention has been described in detail and with respect to present preferred forms which the invention may assume, is not to be limited to such details and forms since many changes and modifications may be made in the invention without departing from the spirit and scope of the invention in its broadest aspects. Hence it is desired to cover any and all forms and modifications which may come within the language or scope of any one or more of the appended claims.

35. What I claim as my invention is:

1. A box formed with end and side walls and an intervening partition wall to form vertically adjacent chambers, the partition wall having a slot near its upper edge providing communication between the chambers, the upper portion of an end wall being separable to expose the adjacent chamber and said slot, the partition wall having an upper flap bent over to form a cover for the other chamber.

45. 2. A box formed with end and side walls and an intervening partition wall to form vertically adjacent chambers, the partition wall having a slot near its upper edge providing communication between the chambers, the upper portion of an end wall being separable to expose the adjacent chamber and said slot, the partition wall having an upper flap bent over to form a cover for the other chamber, the said end wall provided with a flap to be bent over to form a cover for the top of both chambers.

60. 3. A box formed with end and side walls and an intervening partition wall to form vertically adjacent chambers, the partition wall having a slot near its upper edge, the upper portion of an end wall being separable to expose the adjacent chamber and said slot, the partition wall having an upper flap to be bent over to form a cover for the other chamber, said flap having a lock tab to be bent down adjacent the other end wall, the said first mentioned end wall provided with a flap to be bent over to form a cover for the top of both chambers.

70. 4. A box formed with end and side walls and an intervening partition wall to form vertically adjacent chambers, the partition wall having a slot near its upper edge, the upper portion of an end wall being separable to expose the adjacent chamber and said slot, the partition wall having an upper flap to be bent over to form a cover for the other chamber, said flap having a lock tab to

be bent down adjacent the other end wall, the first mentioned end wall provided with a flap to be bent over to form a cover for the top of both chambers, said last mentioned flap having a lock tab to be bent down to lie between the other end wall and the other lock tab.

5. A box blank having when laid out flat and proceeding from left to right thereof, a connecting section, a partition wall section, a connecting section, a rear end wall section, a side wall section, a front end wall section, another side wall section, said partition wall section having a slot near its upper edge, the front end wall section provided with a slit near its upper edge and weakened lines extending upwards from the ends of the slit, flaps depending from the bottom of the side wall sections, a flap extending from the bottom of the rear end wall section, a lock tab at the bottom of said last mentioned flap, a flap extending from the top of the front end wall section and a lock tab connected thereto, a flap extending from the top of the partition wall section and a lock tab connected thereto.

6. A box blank having when laid out flat and proceeding from left to right thereof, a connect-

ing section, a partition wall section, another connecting section, a rear end wall section, a side wall section, a front end wall section, another side wall section, the partition wall section having a slot near its upper edge, the front end wall section provided with a slit near its upper edge and weakened lines extending upwardly from the ends of the slit, flaps depending from the bottom of the end wall sections, flaps extending upwardly from said end wall sections, a flap extending upwardly from the top of the partition wall section, said last mentioned flap having a horizontal weakened medial line thereon.
